UNITED STATES PATENT OFFICE.

ANNON W. HOLT, OF MENOMONIE, WISCONSIN.

DOOR-LATCH.

1,387,888.

Specification of Letters Patent. Patented Aug. 16, 1921.

Application filed October 26, 1920. Serial No. 419,674.

To all whom it may concern:
Be it known that I, ANNON W. HOLT, a citizen of the United States, residing at Menomonie, in the county of Dunn and State of Wisconsin, have invented certain new and useful Improvements in Door-Latches; and I do hereby declare the following to be a full, clear, and exact description of the invention, such as will enable others skilled in the art to which it appertains to make and use the same.

My invention relates to door latches of the type having a spring projected latch bolt that will automatically interlock with a latch plate on a door frame when a door is closed, and that may be released from the latch plate by a shaft operative on a tumbler for the latch bolt and having an operating knob at each side of the door. The object of my invention is to render the shaft of such a latch operative and inoperative on the tumbler, at will, so that when the door is closed, it cannot be opened from the outside by turning the respective knob. The improved latch is especially adapted for use on bathroom doors or other doors that are simply latched for the sake of convenience.

To the above end, generally stated, the invention consists of the novel devices and combinations of devices hereinafter described and defined in the claims.

In the accompanying drawings, like characters indicate like parts throughout the several views.

Referring to the drawings:

Figure 1 is a fragmentary view principally in vertical section taken through a door, and a mortise latch having the invention incorporated therein, said invention being designed for a door hinged to swing outward;

Fig. 2 is a view corresponding to Fig. 1 with the exception that the knob-equipped operating shaft is moved into position to release the tumbler;

Fig. 3 is a perspective view showing the operating shaft and interlocked with the tumbler; as shown in Fig. 1;

Fig. 4 is a perspective view of the operating shaft released from the tumbler, as shown in Fig. 2;

Fig. 5 is a modification showing a different means for limiting the endwise movement of the operating shaft;

Fig. 6 is a view corresponding to Fig. 5

with the exception that the operating shaft is moved into position to release the tumbler;

Fig. 7 is a view corresponding to Fig. 1 with the exception that the invention is designed for a door hinged to swing inward;

Fig. 8 is a view corresponding to Fig. 7 with the exception that the knob-equipped operating shaft is latched against turning movement;

Fig. 9 is a perspective view of the inside knob shown in Figs. 7 and 8;

Fig. 10 is a modification of the invention as shown in Figs. 7 and 9 designed for use in connection with a door hinged to swing outward;

Fig. 11 is a view corresponding to Fig. 10 with the exception that the operating shaft is latched against turning movement;

Fig. 12 is a detail view with some parts sectioned on the line 12-12 of Fig. 11; and

Fig. 13 is a fragmentary perspective view of the knob shown in Figs. 10, 11 and 12.

Referring first to the invention shown in Figs. 1 to 4 inclusive, the numeral 14 indicates a door which may be assumed to be hinged for outward swinging movement and provided with a mortise latch 15. This latch 15 is provided with the customary sleeve-like latch bolt actuating tumbler 16 having an axial passageway that is square in cross-section to receive the correspondingly formed knob-equipped operating shaft. Formed with the tumbler 16 are the ordinary oppositely projecting latch bolt operating lugs 17 and which tumbler is yieldingly held in an intermediate position by a spring, not shown. As is well known, the latch bolt of such a latch is spring projected and arranged to be cammed into a retracted position by engagement with a latch plate during the closing movement of a door, without turning the knob-equipped operating shaft. To retract the latch bolt, it is necessary to turn the knob-equipped shaft and thereby cause a turning movement of the tumbler 16 and its lug 17. The parts thus far described, are of standard and well known construction.

The tumbler 16 is held in the latch casing against axial movement but free to turn by coöperating flanges 18 on said tumbler and latch casing. Secured to each side of the door 14, is an escutcheon 19 having an annular socket 20 axially alined with the tumbler 16 and a bore in the door.

An operating shaft 21 for the tumbler 16, is mounted therein, for endwise sliding movement and provided with inner and outer end sections 22 and 23, respectively, 5 and an intermediate section 24. The shaft end sections 22 and 23 are square in cross-section and the intermediate shaft section 24 is round in cross-section and, of such length when the shaft 21 is adjusted, as 10 shown in Fig. 2, to freely rotate in the tumbler 16. To the shaft section 21 is secured a collar 25 arranged to permit said shaft to be adjusted endwise to carry a portion of the shaft section 22 into the tumbler 16 and thereby latch said shaft to the tumbler for rotation therewith, as shown in Fig. 1. This collar 25 affords a stop arranged to engage the tumbler 16 to limit 15 the endwise movement of the shaft section 22 into said tumbler, as shown in Fig. 1, and to engage the adjacent escutcheon socket 20 to position the round shaft section 24 in the tumbler 16 for free rotation therewith.

25 Inside and outside hollow knobs 26 and 27, respectively, having hubs 28 and 29, respectively, are connected to the shaft 21, by providing said hubs with axial passageways that are square in cross-section, to receive 30 the respective shaft sections 22 and 23 for common rotation therewith. The ends of the hubs 28 and 29 extend into the escutcheon sockets 20, and the former of said hubs is free for turning, and axial movements and the latter of said hubs is free for turning movement, but held against axial movement, by forming thereon, an annular bead 30 held by the converging walls 35 of the respective escutcheon socket 20.

40 The hub 28 is detachably secured to the shaft section 22 for axial adjustments thereon, by a screw 31 arranged to be screwed into any one of a plurality of holes 32 in said shaft section. The shaft section 45 23 is releasably secured to the hub 29 by a yielding-latch 33 in the form of a flat spring located in said hub and having pressed therefrom, a detent 34, arranged to enter either one of a pair of longitudinally spaced 50 latch notches 35 formed in said shaft section. The purpose of providing the shaft 21 with a plurality of longitudinally spaced holes 32 and latch notches 35, is to permit the latch to be applied to doors of varying 55 thicknesses. The latch 33 is arranged to hold the shaft 21 adjusted with its section 22 interlocked with the tumbler 16 so that the said tumbler may be rotated by turning either of the knobs 26 or 27 to retract the 60 latch bolt, not shown.

To close the door 14, which, as previously stated, is hinged to swing outward, the same is pulled closed by the inside knob 26. The 65 pull on the knob 26 during the closing movement of the door 14 will not be suffi-

cient to overcome the spring latch 33 and release the shaft 21. But the pull on the knob 26 as the door closes against the stop on the door frame, will be sufficient to overcome the spring latch 33 and cam the same 70 out of engagement with the respective latch notch 35, thus, releasing the shaft 21 so that the same is moved endwise, together with the knob 26, as shown in Fig. 2. In this position of the shaft 21, its round section 24 75 is brought into complete registration with the tumbler 16 so that the shaft 21 is free to turn in the tumbler 16, when operated by either of the knobs 26 and 27.

The door when thus latched cannot be 80 opened by operating the outside door knob 27 for the reason that it will simply turn in the respective escutcheon socket 20. To open the door from the inside, it is only necessary to press the knob 26 toward the 85 door and thereby carry the shaft section 22 again into interlatching engagement with the tumbler 16. This movement of the knob 26 also automatically connects the shaft 21 to said knob by moving the shaft 90 21 endwise to bring one of its latch notches 35 into a position where the latch 33 can again enter the same. Opening and closing the door 14 from the outside by means of the knob 27 does not, in any way, affect the 95 endwise position of the shaft 21, in respect to the tumbler 16, for the reason that said knob is latched against axial movement.

In case a child should latch the door 14 from the inside, various means may be provided whereby the shaft 21 may be moved endwise to render the same operative on the tumbler 16. For instance, an opening 36 may be formed in the knob 27 through which a button hook, a bent wire or other 100 tool may be inserted for interlatching engagement with a transverse hole 37 in the shaft 21. When the shaft 21 is thus caught by a tool, the same may be readily pulled 105 into interlatching engagement with the 110 tumbler 16.

Referring now to the construction shown in Figs. 5 and 6, the stop collar 25 is dispensed with and the endwise movement of the shaft 21 is limited by providing the hub 115 28 with an annular flange 38 which works in an annular escutcheon socket 39, substituted for the inside escutcheon 20. Said escutcheon socket 39 is provided with an inturned flange 40 arranged to be engaged 120 by the flange 38 to limit the movement of the knob 26 away from the door 14. This form of stop for the shaft 21 is especially adapted for use on doors that vary in thickness as it permits a predetermined endwise 125 movement of the shaft 21. In the construction shown in Figs. 1 and 2, the movement of the shaft 21 is limited by the tumbler 16 and adjacent escutcheon socket 20 and the space between these two points 130

will, of course, vary in doors of different thicknesses, and hence, it would be necessary to have different latches for doors of different thickness.

5 A latch shown in Figs. 7, 8 and 9 is designed for use in connection with doors hinged to swing inward. In this construction, the shaft 21 is made square in cross-section throughout its entire length and is always inter-latched with the tumbler 16 and may be rendered inoperative, at will, by providing means for latching both knobs 26 and 27 against turning movement, in place of rendering the shaft 21 inoperative, in respect 10 to the tumbler 16 as in the latches just described. To latch the knobs 26 and 27 against turning movement, the end of the hub 28 has formed thereon, a key 41 that is rectangular in cross-section and which key 15 is adapted to be inserted by an axial movement of the knob 26 into a correspondingly formed key seat 42 formed in the respective escutcheon socket 20, as shown in Fig. 8.

When the latch is adjusted, as shown in 25 Fig. 7, the key 41 is out of the key seat 42 so that by turning either of the knobs 26 and 27, the shaft 21 may be rotated to operate the tumbler 16. When the door 14 is pushed closed by the knob 26, and said 30 knob given a partial turn to bring its key 41 into alignment with the key seat 42, said knob 26 will be moved axially and thereby carry the key 41 into the key seat 42, which locks both of the knobs against turning 35 movement, as shown in Fig. 8. To open the door 14 when the latch is adjusted, as shown in Fig. 8, the initial pull on the knob 26 will move said knob axially and thereby carry the key 41 out of the key seat 42 and 40 thus release both of the knobs 26 and 27 for free turning movement, to operate the shaft 21, and hence, the tumbler 16.

The construction shown in Figs. 10, 11, 45 12 and 13, is the same as that shown in Figs. 7, 8 and 9, with the exception that the latch is designed for use on doors that are hinged to swing outward. In this construction, the hub 28 is provided with an annular channel 43 adjacent to its key 41 and when adjusted, as shown in Fig. 10, said channel registers with the key seat 42 and permits the knobs 26 and 27 to be turned to operate the shaft 21, and hence, the tumbler 16. When the door is pulled closed by the knob 50 26 and said knob given a turn sufficient to bring the key 41 into registration with the key seat 42, said knob will move axially under the pull on the knob 26 and thereby carry its key 41 into the key seat 42 and 55 60 thereby latch both of the knobs 26 and 27 against turning movement, as shown in Fig.

11. To open the door when the latch is adjusted, as shown in Fig. 11, a pressure on said knob toward the door will carry the key 41 out of the key seat 42 and the channel 65 into registration with the key seat 42, thereby releasing the knobs 26 and 27 for free turning movement.

What I claim is:

1. A latch having inner and outer operating knobs, one of said knobs being movable axially toward and from the other to thereby render the latter temporarily inoperative.

2. A latch having a latch bolt operating tumbler, a shaft operating the tumbler, and knobs for turning the shaft, one of said knobs being swiveled and held against axial movement and the other of said knobs being secured to the shaft for moving the same 80 axially to render the said shaft operative and inoperative, at will, on the tumbler.

3. A latch having a latch bolt operating tumbler, a shaft operating the tumbler, knobs for turning the shaft, one of said knobs being swiveled and held against axial movement and the other of said knobs being secured to the shaft for moving the same 85 axially to render the said shaft operative and inoperative, at will, on the tumbler, and a 90 stop for positioning the shaft either in an operative or inoperative position.

4. A latch having a latch bolt operating tumbler, a shaft operating the tumbler, knobs for turning the shaft, one of said 95 knobs being swiveled and held against axial movement and the other of said knobs being secured to the shaft for moving the same axially to render the said shaft operative and inoperative, at will, on the tumbler, and releasable means for holding the shaft in an operative position.

5. A latch having a latch bolt operating tumbler, a shaft operating the tumbler, knobs for turning the shaft, one of said 105 knobs being swiveled and held against axial movement and the other of said knobs being secured to the shaft for moving the same axially to render the said shaft operative and inoperative, at will, on the tumbler, and a 110 latch for releasably securing the shaft to the swiveled knob in an operative position.

6. A latch having a latch bolt operating tumbler, a shaft operating said tumbler, knobs both rotatable with said shaft, the one 115 knob being swiveled and held against axial movements and the other knob being movable axially toward and from said swiveled knob.

In testimony whereof I affix my signature.

ANNON W. HOLT.
